CLAIM

The ornamental design for a transmitter antenna, as shown and described.

DESCRIPTION

FIG. 1 is a perspective view of a transmitter antenna showing an embodiment of the design of this invention.

FIG. 2 is a front view thereof.

FIG. 3 is a back view thereof.

FIG. 4 is a top view thereof.

FIG. 5 is a left end view thereof.

FIG. 6 is a right end view thereof; and,

FIG. 7 is a bottom view thereof.

The broken line showing a cable is included for the purpose of illustrating non-claimed subject matter and forms no part of the claimed design.
